UNITED STATES PATENT OFFICE.

CARL ERIK ANDERSSON, OF DULUTH, MINNESOTA, ASSIGNOR OF FORTY-FIVE ONE-HUNDREDTHS TO MARGUERITE CUSICK, OF DULUTH, MINNESOTA.

SMOKE-CONSUMER.

1,157,661.

Specification of Letters Patent.

Patented Oct. 26, 1915.

Application filed January 5, 1915. Serial No. 707.

To all whom it may concern:

Be it known that I, CARL ERIK ANDERSSON, a citizen of the United States, residing at Duluth, in the county of St. Louis and State of Minnesota, have invented certain new and useful Improvements in Smoke-Consumers, of which the following is a specification, reference being had therein to the accompanying drawing.

10 This invention relates to a smoke consumer and has for its principal object the production of an efficient means for consuming the materials contained within the smoke before the same is exhausted thereby preventing sparks, refuse, and other objectionable elements from being expelled from the furnace.

Another object of this invention is the production of a smoke consumer having a plurality of consuming pipes through which the smoke which leaves the fire-box is adapted to pass and be consumed since the heat of the consuming pipes will be of sufficient intensity to burn the carbon or volatile matter of the smoke, allowing only the air and burnt gases to be expelled.

Still another object of this invention is the production of a smoke consumer having a draft flue for conveying to the fire-box a draft sufficient to cause the smoke to pass through consuming pipes carried therein whereby the carbon and other elements of the smoke will be consumed at which time the draft will cause the air and gases to be expelled.

Still another object of this invention is the production of a smoke consumer having a plurality of air pipes to which the draft flue is attached whereby the draft from the flue will be evenly exhausted from the air pipes, through the grate, into the fire-box of the furnace for causing a free circulation of the smoke after the same leaves the fire-box.

45 With these and other objects in view this invention consists of certain novel combinations, constructions, and arrangements of parts as will be hereinafter fully described and claimed.

50 Referring to the accompanying drawings:—Figure 1 is a central vertical section through the smoke consumer showing the same in an assembled position and illustrating portions of the device in elevation. Fig. 2 is a front elevation of the assembled

device. Fig. 3 is a section taken on the line 3—3 of Fig. 1 looking in the direction of the arrows. Fig. 4 is a section taken on the line 4—4 of Fig. 1. Fig. 5 is a section taken on the line 5—5 of Fig. 1. Fig. 6 is a section taken on the line 6—6 of Fig. 1. Fig. 7 is a vertical sectional view through the draft funnel. Fig. 8 is a transverse section taken through the draft flue. Fig. 9 is a fragmentary detailed perspective view of the 60 funnel. Fig. 10 is a fragmentary sectional view through a portion of the draft flue. Fig. 11 is a detailed perspective view of a draft operating arm used in connection with this device. Fig. 12 is a fragmentary perspective view of a certain drawer used in connection with this invention. Fig. 13 is a vertical section through a slightly modified form of the draft funnel. Fig. 14 is a side elevation of the draft funnel as disclosed in Fig. 13 showing the outward plate 70 of the fan-casing removed. Fig. 15 is another form of the draft funnel.

Referring to the accompanying drawings by numerals 1 designates the side of the fire box which carries the grate 2 at a spaced distance from the base 3. The distance between the base 3 and the grate 2 forms the ash pit 4 from which the ashes may be removed by the doors 5. The projection 6 carried by a 80 portion of the fire box 1 assists in carrying the boiler casing 7 so as to support the plate 8. This plate 8 extends entirely across the interior of the boiler casing 7 so as to form a separate compartment above the plate 8. 85 The boiler 9 having the longitudinally extending boiler tubes 10 is supported upon this plate 8 so as to allow the end portions of the boiler 9 to be positioned at a spaced distance from the end portions of the boiler 95 casing 7 thereby providing compartments 11 and 12 at each end thereof. The exhaust flue 13 extends above the boiler casing 7 and communicates with the space 12 at one end of the boiler 9. The present invention is 100 used for consuming the carbon contained in the smoke which is generated in the fire box 1 and passes through the boiler tubes 10.

The elbow 14 carried by one end of the fire box 1 is integrally formed upon the draft flue 15 which extends vertically. This draft flue 15 carries an annular shoulder 16 upon which the lower end of the draft funnel 17 rests. This draft funnel 17 is also provided with an integral annular shoulder 18 resting 110

upon the upper end of the draft flue 15. This draft funnel 17 is also provided with the handles 19 for allowing the same to be easily turned in a desired direction to catch 5 the wind for causing the wind to pass down into the draft flue 15. The shoulder 16 is provided with a plurality of notches 20 for the reception of the pivoted finger 21 which is pivotally secured to the draft funnel 17 as 10 shown at 22. It will be seen that by raising the pivoted finger 21 and by grasping the handles 19 the draft funnel 17 may be swung in a desired direction for catching the wind and causing the same to pass downwardly 15 into the interior of the draft flue 15. The finger 21 may then be released and the weight of the finger will cause the same to fall and rest within one of the notches 20 thereby holding the draft funnel in a set 20 position and thus prevent the wind from blowing the funnel around and diminishing the current of air passing down into the draft flue 15. The elbow 14 is also connected to the secondary portion 23 of the 25 draft flue 15 and this secondary portion 23 passes into the opening 24 communicating with the room 25 formed at one end of the drawer 26. This drawer 26 is also provided with openings 27 communicating with the 30 room 25 and the air pipes 28 are positioned within the drawer 26 so as to have their end portions passing through the openings 27 to communicate with the room 25. These pipes 28 are also provided with apertures 29 in 35 their upper portions so that when the air is passed from the flue 15 into the room 25 it will be equally distributed into the air pipes 28 from which it will be discharged through the apertures 29 into the fire box. It is to 40 be observed, however, that the passage of air from the draft flue 15 may be cut off by operating the valve disk 30 by means of the handle 31. When, however, the air passes from the air pipes 28 through the apertures 45 29 it will pass upwardly through the grate 2 and into the fire box 1. The passage of this air into the fire box will cause the fire to burn and therefore it will be necessary to provide a means for consuming the smoke. 50 Upon the grate 2 there is carried a pair of spaced blocks 32 which carry the consuming pipe 33. This consuming pipe 33 has the parallel spaced portions 34 communicating with each other by means of the U-shaped elbow 35. One portion of the parallel consuming pipes 34 carries the funnel 36 while the other portion is provided with the straight pipe 37 extending upwardly and passing through the plate 8 so as to 55 communicate with the compartment 11 formed at one end of the boiler 9. The funnel 36 however is positioned within the fire box 1 so as to have its open portion adjacent the under surface of the plate 8. 60 65 This consuming pipe is adapted to have its parallel portions 34 positioned within the bed of coals in the fire box when the device is in operation. Upon the projection 6 there is positioned a secondary consuming pipe 38 having the elbow 39 extending 70 through the plate 8 and communicating with the compartment 12 at one end of the boiler 9. The opposite end of the consuming pipe 38 has a depending portion 40 terminating in the upwardly bent end 41 which rests 75 upon the grate 2. It will be noted, however, that the upturned end may direct the current of air upwardly into the fire box 1 and will prevent the air currents passing upwardly from the air pipes 28 having admission to the secondary consuming pipe 38. Since the upwardly bent portion 41 and the depending portion 40 of the secondary consuming pipe 38 are positioned within the fire box they will be heated by the fire 80 within the box to a very high degree while the secondary consuming pipe 38 will also be heated owing to the fact that the space between the projection 6 and the plate 8 communicates with the fire box 1. A hood 42 is carried at the upper portion of the compartment 12 and has a reduced neck 43 provided with a valve disk 44. The rod 45 is connected to this valve disk 44 and has a crank portion 46 to which the arm 47 is 90 connected. When the device is in operation, the draft funnel 17 may be swung into position to catch the wind. The wind will then travel down into the flue 15 and thence into the air pipes 28. The air within these pipes 100 will then be expelled through the apertures 29 into the fire box. Since the funnel 36 has its open end positioned so as to receive the air currents as disclosed by the arrows in Fig. 1, the fire which is being built with 105 in the fire box 1 will pass into the funnel and then through the consuming pipe 33. The fire and smoke will then pass through the vertical pipe 37 into the compartment 11 and then through the tubes 10 of the 110 boiler 9. At this time the rod 45 should be turned by means of the arm 47 so as to open the passage-way through the neck 43 of the hood 42. The smoke may then pass into the compartment 12 and be expelled through 115 the neck 43. At this time the valve 48 carried within the secondary consuming pipe 38 will be in a closed position. It will be seen that at this stage the smoke passing from the neck 43 will contain carbon and particles 120 of material which is causing a waste and also the danger of sparks and the objectionable features accompanying the exhaust of smoke. When, however, this action is continued for a short while the consuming pipe 125 will be heated as will the secondary consuming pipe 38 having the depending portion 40. As soon as this has been accomplished, the valve 48 may be opened while the valve disk 44 may be closed. The cur- 130

rent of air will cause the smoke to pass into the funnel 36 and through the parallel portions 34 of the consuming pipe 33. Owing to the fact that this pipe will be positioned 5 within the fire box and within the bed of coals it will be heated to a very high degree and will therefore burn the carbon and other objectionable elements in the smoke as the smoke passes therethrough. As the 10 smoke is then freed from the carbon and other elements, the gases and heated air will pass into the compartment 11 as shown by the arrows in Fig. 1. These gases and air will pass through the tubes 10 of the boiler 15 and then downwardly as shown by the arrows in Fig. 1, into the elbow 39. The gases and air will then pass through the secondary consuming pipe 38 and through the depending portion 40 to be expelled from 20 the upwardly bent portion 41 and secondary consuming pipes 38 into the fire box 1. There is formed, however, upon the depending portion 40 of the secondary consuming pipe 38 an exhaust pipe 49 which communi- 25 cates with the ash pit 4. This exhaust pipe 49 is also provided with a valve disk 50. By having this exhaust pipe 49 when it becomes necessary for the burnt gases and air to pass from the secondary consuming pipe 30 38 and depending portion 40 instead of passing into the fire box 1, the burnt gases and air will pass into the ash pit 4. The doors 5 at this time may be opened so as to allow the burnt gases and air to be expelled 35 from the ash pit. It will be seen that by the use of this exhaust pipe 49 whenever it is necessary for the burnt gases and air to be expelled, they may easily pass from the secondary consuming pipe. If, however, 40 all of the burnt gases and air do not pass from the depending portion 40 and the secondary exhaust pipe 38 they will be passed into the fire box so as to be circulated again. It is however obvious that after passing 45 through the heated exhaust pipe 33 and through the secondary exhaust pipe 38 all the inflammable material of the smoke will be consumed thereby allowing the gases and air to be exhausted without danger of fire 50 by sparks and also eliminating the objectionable features accompanying the escape of smoke in its ordinary condition.

In order to facilitate the conducting of the draft, a reduced tube 51 is carried within 55 the draft flue 15 and extends outwardly and around the outer portion of the draft flue adjacent the valve 30. The tube 51 then extends again into the draft flue 15 as shown at 52 and then extends beneath the 60 elbow 14 and the outer portion of the fire box so as to extend again into the fire box as shown at 53 above the grate 2 and then have its end extend into the vertical portion 37 of the consuming pipe 33 as shown at 54. 65 As the air passes downwardly into the draft

flue 15 by means of the draft funnel 17 a portion of the current of air will pass downwardly through the tube 51 and into the vertical portion 37 of the consuming pipe 33. This will cause the air currents through 70 the consuming pipe 33 to be heated owing to the fact that the admission of the air current by the tube 51 will be adjacent the portion of the consuming pipe 33 from which the air and gases of the burnt smoke 75 are expelled. A secondary tube 55 is also carried within the flue 15 and has its lower portion 56 extending from the flue 15 so as to have the horizontal portion 57 extend beneath the grate 2 and be connected to the 80 vertical portion 58 communicating with the interior of the secondary consuming pipe 38 as shown at 60. This tube will also receive a direct supply of air from the funnel 17 and will convey this air into the secondary consuming pipe 38 for causing a current 85 of air upon the opposite side of the boiler casing to that upon which the draft flue is carried.

Each air pipe 28 has at its open end a 90 valve disk 61 having a crank arm 62 to which the lever 63 is connected by passing the crank portions of the valves carried by the air pipes 28 into the apertures 64 formed in the lever 63. If some of the cinders or 95 coals from the fire box fall through the grate and into the air pipes 28 by passing through the openings 29 the lever may be pushed for swinging the valve disk 61 thereby opening the free end of the air pipes 28. 100 The force of the air within the air pipes 28 will blow the refuse from the interior of the air pipes. The lever may again be pushed for closing the open ends of the air pipes whereby the currents of air will be directed 105 into the fire box. The draft flue 15 may also be provided with a stop-cock 65 for allowing any water which might be contained within the draft flue to be easily expelled therefrom. In order to support the drawer 110 26 in its correct position there are provided a plurality of brackets 66 which are fixedly secured to the side portions of the casing forming the ash pit at a spaced distance 115 below the grate 2.

By referring to Figs. 13 and 14 it will be seen that a slightly modified form of a draft funnel has been produced to which the funnel 67 has a fan housing 68 connected which is closed by the plate 69. Within 120 this housing, the fan 70 is positioned and adapted to be rotated by the groove-pulley 71. The reduced hood 72 is formed integral within this draft funnel 67 so as to direct the current of air from the fan 70 downwardly into the draft flue 15. This draft funnel performs all of these functions similar to the funnel disclosed in the preferred form and the only change in this form of the funnel is in the fact that the fan 70 may be 125 130

used to increase the air current provided there is not a sufficient amount of air passing into the funnel to supply the several portions of the consumer with the air currents.

6 By referring to Fig. 15 it will be seen that another form of the funnel member has been produced in which a sleeve 73 may be carried upon the draft flue 15 so as to allow the annular flange 74 to rest upon the upper 10 portion of the draft flue 15. In this form of the device, however, there may be provided a plurality of reduced funnels 75 which are so positioned within the upper portion of the sleeve 73 as to allow their 15 lower portions to rest upon the annular flange 74 while their enlarged outer portions will rest upon the upper portion of the sleeve 73 and furthermore the size of the bodies of these funnels will cause the 20 same to remain in snug engagement within the sleeve 73. This form of the invention may be also provided with a plurality of tubes 76 extending upwardly into the funnel members 75 and then communicating with 25 the pipe 77 which is used instead of the tubes 51 and 55 of the preferred form of the invention.

From the foregoing description it will be seen that an efficient smoke consumer has 30 been produced in which the smoke must pass through the consuming pipes which are heated so as to burn the smoke and thus cause the burnt gases and air to be easily 35 discharged from the consumer while the consumer is also provided with an efficient means for supplying a draft or current of air through the smoke consumer so as to cause the smoke to be readily passed through the several portions of the device for being 40 consumed before it is expelled.

What I claim is:

1. In a smoke consumer the combination with a fire box and a boiler, smoke consuming pipes positioned within said fire box 45 and communicating with said boiler, a drawer carried beneath said smoke consuming pipes, a plurality of air pipes carried within said drawer, a draft flue carried by said fire box and communicating with said 50 drawer, said draft flue being adapted to convey a current of air into said drawer and into said air pipes whereby the air may be passed up into said fire box for causing the smoke to be passed through said smoke 55 consuming pipes whereby the inflammable material of the smoke may be burnt at which time the burnt gases may pass through said boiler and be exhausted.

2. In a smoke consumer the combination 60 with a fire box and a boiler, smoke consuming pipes carried within said fire box and communicating with said boiler, a plurality of air pipes positioned beneath said smoke consuming pipes, means for supporting said 65 air pipes, a draft flue carried by said fire

box and communicating with said air pipes, said draft flue having a revoluble funnel carried upon the upper end thereof, said funnel being adapted to convey wind into said draft flue and then to said air pipes 70 whereby the air may be expelled into said fire box for causing the smoke within the fire box to pass through said smoke consuming pipes whereby the inflammable material of the smoke may be burnt at which time the 75 burnt gases may pass through said boiler and be expelled.

3. In a smoke consumer the combination with a fire box and with a boiler, a primary smoke consuming pipe carried within said fire box and communicating with one end of said boiler, a secondary smoke consuming pipe carried at the opposite end of said fire box and communicating with the opposite end of said boiler, said auxiliary smoke consuming pipe provided with an upwardly bent end, means for supplying said fire box with a supply of air for driving the smoke within said fire box through said first mentioned smoke consuming pipe whereby the 85 inflammable material of the smoke will be burnt and the burnt gases will pass through said boiler and then through said secondary smoke consuming pipe into said fire box, means connected with said secondary supply pipe for exhausting the burnt gases when necessary.

4. In a smoke consumer the combination with a fire box and a boiler, smoke consuming pipes carried within said fire box and 100 communicating with said boiler, a draft flue carried by said fire box and a revoluble funnel carried by said flue, whereby air may be supplied to the lower portion of said fire box for causing a circulation of the smoke 105 through said smoke consuming pipes, and means carried by said draft flue and communicating with said smoke consuming pipes for permitting a secondary supply of air for facilitating in directing the air current 110 within the smoke consuming pipe.

5. In a smoke consumer the combination with a fire box and a boiler, smoke consuming pipes carried within said fire box and communicating with said boiler, a draft flue carried by said fire box, means carried by said draft flue and communicating with said smoke consuming pipes for forming a secondary air supply communicating with said fire box at a distance above the lower portion thereof, a revoluble funnel carried upon the upper portion of said draft flue, a fan casing formed upon said funnel, said funnel provided with an integral internal-hood, a fan carried within said fan casing, means 125 for rotating said fan whereby a current of air may be directed by said hood into said draft flue and secondary air supply and then into said fire box for causing the smoke from said fire box to circulate freely where- 130

by the inflammable elements which have been burnt and the burnt gases may be exhausted.

6. In a smoke consumer the combination with a fire box and a boiler, smoke consuming pipes carried within said fire box and communicating with said boiler, a draft flue carried by said fire box and communicating with the lower portions thereof, a sleeve 10 revolvably mounted upon the upper portion of said draft flue, an annular flange formed within said sleeve, a plurality of reduced funnels extending into said sleeve and resting upon said flange, the upper ends of said 15 funnel overhanging the upper portions of said sleeves, said funnels being adapted to direct a current of air into said draft flue whereby the air will be passed into said fire box for causing the smoke to pass 20 through said smoke consuming pipes for burning the inflammable elements thereof, and means for exhausting the burnt gases from one of said smoke consuming pipes.

7. In a smoke consumer, the combination with a fire box, and a boiler, smoke consuming pipes carried within said fire box and communicating with said boiler, a drawer carried beneath said fire box, a room formed

integral upon one end of said drawer, said drawer provided with openings communicating with said drawer and room, an air supply means communicating with said room, air pipes positioned within said drawer and extending into said openings, said air pipes having the ends within said room open and the opposite ends closed, said air pipes provided with apertures in their upper portions, said air supply means being adapted to direct air into said room, at which time the air will pass into said air 40 pipes and be discharged therefrom through said apertures into said fire box, thereby forming an air current through the fire-box for directing the smoke through the superheated smoke consuming pipes, and thus 45 cause the inflammable material thereof to be burnt, at which time the burnt gages may be expelled after passing through said boiler.

In testimony whereof I hereunto affix my 50 signature in presence of two witnesses.

CARL ERIK ANDERSSON.
